UNITED STATES PATENT OFFICE

LEO J. GRUBMAN, OF BELLE HARBOR, NEW YORK

EYE MOUNTING FOR DOLLS

Application filed February 7, 1927. Serial No. 166,372.

This invention relates to eye mountings for dolls of that type wherein means is provided and secured in fixed relation to the wall structure of the head for supporting or retaining an oscillatory eye setting with the spaced eye members thereof accurately related to the eye openings in the head wall and which permits of a free non-binding oscillatory motion of the respective eye members in relation to said wall.

In several co-pending patent applications filed by me I have described certain devices of this kind wherein the mounting or retaining means and the oscillatory eye setting are first associated with each other and then inserted together through the neck opening of the doll head and the mounting or retaining means attached or secured in fixed relation to the head wall with the spaced eye members of the setting in spaced cooperative relation to the eye openings in said wall. My present invention is distinguished in its fundamentals from such prior inventions in that the supporting or retaining means is first applied and secured in fixed relation to the front wall of the doll head before the two halves or sections of the head are permanently joined or connected with each other, and the oscillatory eye setting may be subsequently inserted through the neck opening of the otherwise closed head and arranged in cooperative assembled relation with the supporting or retaining means and the eye openings in the head wall without necessitating the use of a tool of any kind or special skill on the part of the workmen. Thus, it becomes possible for the doll manufacturer to carry the heads equipped with the supporting or retaining means in stock and apply the oscillatory eye settings thereto as the demand may require without separating the head sections or cutting an opening in the top of the head as heretofore practiced in this art.

In accomplishing the above purpose, I

provide means projecting inwardly from the front wall of the doll head and upon which the shaft or axis of the oscillatory eye setting is adapted to be supported for movement towards and from the front wall of the doll head together with a retaining member having relatively yieldable parts permitting of the assemblage of the shaft or axis upon said supporting means and preventing possible displacement of said shaft and of the eye setting from its operative relation to said supporting means and the front wall of the doll head.

In one practical embodiment of the invention, I prefer to provide the front wall of the doll head with an internally formed recess adapted to receive cooperatively associated supporting and retaining members for the eye setting, and it is an important feature of my invention to provide a simple and easily applied fastening member, common to the supporting and retaining members and whereby the latter may be permanently secured in fixed relation to each other and to the head wall.

It is also a further general object of the invention to provide an eye mounting for dolls of the above character in which the several parts may be rapidly produced in the form of simple sheet metal stampings so that the device as a whole may be manufactured at relatively low cost and will not add materially to the selling price of such dolls equipped with oscillatory eye settings and mounting or supporting means therefor as heretofore known to the art.

With the above and other objects in view, the invention consists in the improved eye mounting for dolls and in the form, construction and relative arrangement of its several parts as will be hereinafter more fully described, illustrated in the accompanying drawings, and subsequently incorporated in the subjoined claims.

In the drawings, wherein I have illus-

trated several simple and practical embodiments of the invention, and in which similar reference characters designate corresponding parts throughout the several views,—

5 Figure 1 is a rear elevation of the front half or section of a doll head to which the improved eye mounting is adapted to be applied;

10 Fig. 2 is a central vertical sectional view showing the several parts of the eye mounting as secured in their final assembled positions upon the front wall of the doll head;

15 Fig. 3 is a similar view showing the front and rear sections of the doll head joined together and illustrating an oscillatory eye setting arranged in operative relation with respect to said mounting or retaining means, parts of the latter being shown in dotted lines as displaced from their normal positions in 20 the operation applying the eye setting;

25 Fig. 4 is a horizontal sectional view taken on the line 4—4 of Fig. 2 and showing the normal condition of the fastening member before it is engaged with the structure of the head wall to fasten the several elements in place;

30 Figs. 5, 6 and 7 are detail perspective views of the supporting member, the retaining member, and the fastening member respectively of the eye mounting;

Fig. 8 is a rear elevation of the front wall of the doll head similar to Fig. 1, showing the mounting and the eye setting applied thereto;

35 Fig. 9 is a horizontal sectional view taken substantially on the line 9—9 of Fig. 8;

Fig. 10 is a vertical sectional view similar to Fig. 3 showing a slightly modified form of the invention, and

40 Fig. 11 is a view similar to Fig. 8 of said modified construction.

In the application and use of the present invention, the doll head, in accordance with the practice now generally followed in the art is molded or otherwise shaped or fashioned from wood pulp, papier-mâché or other composition material in separate front and rear halves or sections herein designated by the numerals 5 and 6 respectively. These 45 front and rear sections of the head are subsequently permanently joined together along their meeting edges indicated at 7 by the application thereto of glue or other suitable adhesive. The front half or section 5 of the doll head is of course, provided in the molding operation with the usual facial features in proper proportion and relation to each other and through this front wall of the head the spaced eye-shaped openings 8 are cut. 55 The inner side of the head wall at each of these openings 8 is milled out to provide the eye member receiving sockets or cavities 9. At the outer side of each of these cavities, the 60 opposite sides of the head wall are provided with the horizontal grooves 10 therein for a

purpose which will hereinafter be explained.

The structure of the front wall of the doll head between the cavities 9 and above the same is relatively thick, and in this part of the wall structure a suitably shaped recess is formed. As herein shown, this recess includes a comparatively wide rectangular upper section 11 above the sockets 9, a narrow section 12 extending downwardly from the lower side of the section 11 between the sockets 9, and a slightly widened lower end section 13. The base walls or surfaces of all of these recess sections are disposed in a common perpendicular plane as shown in Fig. 2 of the drawings which is preferably disposed at substantially right angles to a common horizontal plane intersecting the centers of the eye openings 8.

Before the two halves or sections 5 and 6 of the doll head are permanently connected or joined to each other a supporting member 14 is first positioned in the recess in the front wall of the doll head. As shown in Fig. 5 of the drawings, this supporting member consists of a stamped metal plate and includes an upper rectangular section 15 adapted to snugly fit within the upper section 11 of the recess.

A relatively narrow neck 16 extends downwardly from the lower edge of the part 15 of said supporting member and is adapted to be received in the section 12 of the recess in the head wall, said neck adjacent its lower end and at the opposite side edges thereof being provided with the supporting arms 17 projecting from one side of the neck 16 in parallel relation to each other and substantially at right angles to the plane of said supporting member.

At their extremities, the upper edge of each of these supporting arms is provided with a horizontally extending shoulder or seat 18 and the end edge of the arm is rounded or upwardly curved to this shoulder as shown at 19. The purpose of this construction will also be hereinafter explained in detail.

After the supporting member has been arranged in the recess of the head wall, the retaining member shown in Fig. 6 of the drawings is also positioned in said recess and upon the supporting member.

This retaining member, which is likewise produced in the form of a sheet metal stamping includes a rectangular part 20 of substantially the same dimensions as the part 15 of the supporting member. A resiliently yieldable elongated tongue 21 is integrally connected at one of its ends by the angular part 22 with the part 20 substantially centrally of the latter and is normally positioned in laterally spaced relation to the part 20 and parallel therewith.

The free end of this yieldable tongue 21 is slightly curved or bent outwardly as indicated at 23. At each side of the tongue 21 and normally positioned at substantially right angles thereto, a resiliently

130

yieldable arm 24 is integrally connected at one of its ends with the part 20. The other end portion of each of these arms is bent downwardly and inwardly as at 25 to provide an open loop, the extremity of said arm intersecting the plane of the tongue 21 in the normal position of the latter as clearly shown in Fig. 2 of the drawings. As will also be evident from reference to Figs. 3 and 6 of the drawings, when this retaining member is assembled in superposed relation upon the supporting member 14, the extremities of the looped ends 25 of the arms 24, seat upon the shoulders 18 of the arms 17 so that the said arms 17 and 24 in conjunction with each other provide normally closed elongated loops extending inwardly from the front wall of the doll head and between which the vertically positioned relatively yieldable tongue 21 extends downwardly below the arms 17.

The supporting member and the retaining member are adapted to be fixedly secured upon the head wall against movement relative to each other by means of a common fastening member shown in detail in Fig. 7 of the drawings. This fastening member consists of a stamped resilient sheet metal plate 26 of a general rectangular form which is centrally provided with an opening 27 therethrough. At opposite sides of this opening, the plate is provided with transversely extending concavo-convex sections 28, and the ends of the plate at the opposite longitudinal edges thereof are formed with the impaling spurs 29.

The fastening member 26 is adapted to be assembled with the retaining member before the latter is arranged in position. This may be done by simply displacing the tongue 22 and resilient arms 24 of the retaining member relative to each other so that the tongue 21 may be passed through the opening 27 in the plate 26 and said plate moved along said tongue to a position in parallel relation to the part 20 of the retaining member and in contact therewith, the concave sides of the sections 28 of the fastening plate being opposed to the retaining member as shown in Fig. 4 of the drawings. By now applying pressure against the convex sides of the sections 28 of plate 26, said sections may be flattened out, thus expanding the ends of the resilient plate in opposite directions and causing the spurs 29 thereon to become embedded or impaled in the structure of the doll head wall at the opposite ends of the upper section 11 of the recess therein as shown in Figs. 8 and 9 of the drawings.

After the several parts of the mounting or retaining means for the eye setting have thus been applied and secured to the front wall of the doll head, the two sections 5 and 6 of the doll head are permanently joined or secured to each other so that the head is completely

closed with the exception of the opening through the neck thereof. Through this opening the oscillatory eye setting is adapted to be inserted and arranged in cooperatively supported relation with respect to the front wall of the doll head and the eye openings therein.

In the embodiment of the invention which I have selected for purposes of illustration, the oscillatory eye setting includes a shaft 30 or axis 30. The eye members 31 in the form of hollow shells which are suitably provided with the representation of eyelids and pupils simulating the human eye, are provided with suitably formed openings in opposite sides 70 thereof to snugly receive the shaft 30. Oscillatory motion is transmitted to these spaced eye members through the medium of a stamped sheet metal plate 32 having apertured lugs 33 extending within the respective 80 eye shells and loosely receiving the shaft 30 whereby said plate is loosely suspended from the shaft for freely oscillating motion. Spaced parts of this plate 32 are in contact with the rear edges of the respective eye members 31, and below the eye members said plate is provided with an angularly projecting part 34 carrying a suitable weight 35. To this weighted lower portion of the plate the upper end of a resiliently yieldable stop spring 95 90 36 is pivotally connected. The free end of this stop spring is adapted for contact with the inner side of the head wall at the neck thereof to yieldingly limit the oscillatory motion of the eyes to their open positions. 100

The upper portion of the plate 32 of the eye setting is centrally cut away or recessed as at 37 to accommodate the downwardly extending end of the tongue 21 of the retaining member in the oscillatory movement of said plate, and at each side of this central slot in the plate 32 the plate is further cut away or recessed as at 38 to accommodate the arms 17 of the supporting member. The edges 39 of the plate at the lower side of these cut-outs 38 constitute stop shoulders 110 adapted for contact with the looped end portions 25 of the arms 24 of the retaining member to limit the oscillatory movement of the eyes to their closed positions. 115

In the application of the eye setting to its operative position within the doll head, the pivoted yieldable stop member 36 is turned or moved to a position in substantially parallel relation with the part 34 of the plate 32 so that the eye setting may be readily passed upwardly through the neck opening of the doll head. The eye setting is then turned in the hand until the shaft or axis 30 thereof is positioned transversely of the doll head and is located by the sense of touch below the arms 17. The shaft is then moved inwardly in contact with these arms and around the curved rear ends 19 thereof into engagement with the ends of the loops 25. 125 130

By then applying an upward pressure against the shaft, the extremities of these loops are forced upwardly off of the shoulders or seats 18 and the arms 24 are sprung upwardly to substantially the position shown in dotted lines in Fig. 3 of the drawings, it being also understood of course, that in this movement of the shaft, the downwardly extending resilient tongue 21 is displaced from its normal position to substantially the dotted line position shown in said figure. As the shaft of the eye setting is moved upwardly against the resistance of the spring arms 24, it is also moved forwardly and upon the upper edges of the arms 17 beyond the extremities of the loops 25. The eye setting is then released and the hand withdrawn through the neck opening of the head. The spring arms 24 and the tongue 21 instantly resume their normal positions, the loops 25 being closed by the engagement of the extremities thereof on the seats 18 while the tongue 21 bears against the rear side of the shaft 30 and yieldingly urges the same forwardly on the supporting arms 17, thus holding the spaced eye members 31 in close engagement with the walls of the respective eye sockets 29.

When the doll head is tilted from the perpendicular position at the required angle so that the center of gravity of the weighted pendulum plate of the eye setting is positioned inwardly of the center of the shaft 30, said shaft will freely turn or oscillate upon the supporting arms 17. The weight of the eye setting is thus transmitted to the spring tongue 21 and this tongue will yield sufficiently to free the eye members from excessive frictional contact with the wall of the sockets 9, thus permitting of a non-binding uninterrupted oscillating motion of the eye members from their open to their closed positions. When the doll head is returned to its upright position, the reverse movement of the eye members of course, takes place, and they are again held in close contact with the walls of the eye sockets. This movement of the eye setting is cushioned or yieldingly limited by the contact of the free end of the spring stop 36 with the neck wall of the doll head, it being understood of course that this spring stop has been pivotally moved relative to the plate of the eye setting to a longitudinally projecting position with respect thereto as shown in the drawings.

In Figs. 10 and 11 of the drawings, I have illustrated a slightly modified form of the invention wherein the supporting member shown in Fig. 5 is dispensed with, and two inwardly projecting supporting lugs 40 are integrally formed with the structure of the front wall of the doll head at opposite sides of the lower end portion 13 of the recess therein. These lugs are of substantially the same form as the supporting arms 17 of the member illustrated in Fig. 5 and are pro-

vided at their ends in their upper surfaces with the shoulders or seats 18 and with the rounded or convex end faces 19'. In this construction therefore, it will be understood that the retaining member as shown in Fig. 6 of the drawings is first arranged in the upper part of the recess in the head wall with the rectangular portion 20 engaged upon the base thereof and with the fastening member or plate shown in Fig. 7 engaged upon said part 20 of the retaining member and anchored at its ends in the structure of the head wall as above explained. The resilient arms 24 of the retaining member are of precisely the same form as heretofore described and the extremities of the looped ends thereof coact with the lugs 40 in precisely the same manner as when this retaining member is used in conjunction with the separate supporting member illustrated in Fig. 5. By the elimination of the metallic supporting member, the internal recess in the head wall which receives the retaining member and the fastening plate may be of less depth and the wall thickness can be decreased proportionately. Also by reducing the number of essential parts comprising the mounting or retaining means the manufacturing cost of this modified construction may be somewhat less than the construction first described. It will be understood that the application or arrangement of the eye setting in cooperative relation with the eye mounting or retaining means is accomplished in the same manner as above explained, and in the use of either construction, as the shaft 30 of the eye setting is moved upwardly around the ends of the supporting arms 17 or the lugs 40, the ends of the shaft 30 are accommodated in the grooves or recesses 10 in the opposite sides of the head structure. However, it will be noted from reference to Fig. 8 that the ends of this shaft are not in bearing contact with the lower walls of said grooves, but the shaft is supported solely by means of the spaced arms or lugs.

From the foregoing description considered in connection with the accompanying drawings, the construction, manner of use or application and several advantages of the described embodiments of the invention will be clearly understood. It will be seen that the novel feature of the present disclosure consists essentially in the provision of a mounting or retaining means for the oscillatory eye setting which is applied or secured in fixed relation to the wall of the doll head independently of the eye setting during the course of manufacture of the head, and said mounting or retaining means including parts relatively displaceable under pressure by the engagement of a part of the eye setting subsequently inserted through the neck opening thereof whereby said setting may be arranged in operatively supported

relation with the doll head wall and with the eye members of said setting properly positioned in said sockets. In so far as I am aware, it is new in this art to provide a device of this character whereby the eye setting may be easily and quickly applied in its operative position by hand through the neck opening of the doll head and without requiring that the top of the head be opened or the use of a tool of any kind. Further, I believe it to be new in this art to provide such a mounting or retaining means for the eye setting wherein the relatively displaceable parts are so co-related or arranged relative to each other and with respect to the supports upon which the setting oscillates that the displacement of the setting from its operative position with relation to the head wall, as when the head is subjected to violent shock or jar is rendered impossible, while at the same time, the setting is yieldingly urged forwardly to hold the eye members in close association with the walls of the eye setting, and yet obviate such frictional resistance due to contact between the eye members and the socket walls as would tend to retard or impede the free oscillating motion of the eye members. I have herein illustrated several practical structural examples of my invention whereby these desirable results are obtained. Nevertheless, it is possible that similar results might also be secured in various other alternative forms of my invention, and I accordingly reserve the privilege of resorting to all such legitimate changes in the form, construction and relative arrangement of the several parts as may be fairly embodied within the spirit and scope of the invention as claimed.

46 I claim:

1. In combination with a doll head, supporting and retaining means for an oscillatory eye setting mounted upon the front wall of said head, said means including a bearing fixed in relation to said wall and a movable latch part normally engaged with said bearing and vertically movable from its normal position to permit the axis of an eye setting inserted through the neck opening of the doll head to be mounted upon the bearing in operative relation to spaced eye openings in the head wall, and additional means yieldably holding the eye setting in its normal operative position on the bearing and out of contact with said latch means.

2. In combination with a doll head, supporting and retaining means for an oscillatory eye setting mounted upon the front wall of said head, said means including a bearing fixed in relation to said wall and a resiliently yieldable part normally engaged with said bearing and vertically movable by a part of an eye setting inserted through the neck opening of the doll head and displaceable under pressure of said part to permit the setting

to be mounted upon the bearing in operative relation to spaced eye openings in the head wall, and additional means yieldably holding the eye setting in its normal operative position on the bearing and out of contact with said latch means. 70

3. In combination with a doll head, supporting and retaining means for an oscillatory eye setting on the front wall of the doll head, said retaining means including spaced lugs and resiliently yieldable parts having end portions normally engaged with the respective lugs and projecting inwardly therefrom for engagement by the shaft of an eye setting inserted upwardly through the neck 80 opening of the doll head whereby said parts are displaceable from their normal positions to permit said axis to be positioned upon the upper edges of said lugs, and means yieldingly urging the eye setting forwardly on the 85 lugs to hold the eye members thereof in cooperative relation with the respective eye openings in the doll head wall.

4. In combination with a doll head, supporting and retaining means for an oscillatory eye setting on the front wall of the doll head, said retaining means including spaced lugs and resiliently yieldable parts having end portions normally engaged with the respective lugs and projecting inwardly 90 therefrom for engagement by the shaft of an eye setting inserted upwardly through the neck opening of the doll head whereby said parts are displaceable from their normal positions to permit said axis to be positioned upon the upper edges of said lugs, and an additional resiliently yieldable part positioned 95 between said first named parts adapted to coact with the axis of the eye setting and urge the same forwardly on said lugs to hold the spaced eye members of the setting in cooperative relation with the eye openings in the doll head wall. 100

5. In combination with a doll head, supporting and retaining means for an oscillatory eye setting including a normally closed guide loop projecting inwardly from the front wall of the doll head at substantially right angles to the plane thereof and said loop having a resiliently yieldable part displaceable under the pressure of the axis of an eye setting inserted upwardly through the neck opening of the doll head whereby said axis may be positioned within said loop for movement in relation thereto towards and 115 from the front wall of the doll head in the operative position of the eye setting, and an additional resiliently yieldable member to coact with the axis of the eye setting and urge the same forwardly to hold the eye 120 members thereon in cooperative relation with spaced eye openings in the doll head wall. 125

6. In combination with a doll head, a normally closed guideway projecting inwardly from the front wall of the head said guide- 130

way including a movable member, and a resiliently yieldable element associated with said guideway adapted to be displaced from its normal position to permit a part of an eye setting inserted through the neck opening of the head to be engaged with said movable member to move the latter so that said part may be positioned in the guideway, and said element adapted to coact with said part of the eye setting to yieldingly urge the setting forwardly and hold the spaced eye members thereof in cooperative relation with the respective eye openings in the doll head wall.

7. In combination with a doll head, spaced normally closed guide loops projecting inwardly from the front wall of the doll head at substantially right angles to the plane thereof, each of said loops having a lower resiliently separable part displaceable under the pressure of the axis of an eye setting inserted upwardly through the neck opening of a doll head whereby said axis may be positioned within said loops and supported thereby for movement towards and from the front wall of the doll head, and a resiliently yieldable member fixed to the wall of the doll head and adapted to coact with the axis of the eye setting to urge the same forwardly in said guide loops and hold the spaced eye members thereon in cooperative relation with the respective eye openings in the doll head wall.

8. In combination with a doll head having front and rear sections adapted to be permanently joined to each other, a member for supporting an oscillatory eye setting upon the front section of the doll head, a separate retaining member adapted to be superimposed upon the said supporting member and having means to prevent displacement of the eye setting out of cooperative relation with the supporting member, and means engaged with the retaining member and having parts fixed in the head wall for securing the supporting and retaining members in applied position to the front wall of the doll head before the head sections are secured to each other.

9. In combination with a doll head having front and rear sections adapted to be permanently joined to each other, a member for supporting an oscillatory eye setting upon the front section of the doll head, a separate retaining member adapted to be cooperatively associated with said supporting member to prevent displacement of the eye setting out of cooperative relation with the latter, means superimposed upon the retaining member and fixed to the doll head for securing the supporting and retaining members in applied position upon the front wall of the doll head, and said retaining member including movable parts coacting with opposed parts of the supporting member and adapted to be engaged by the axis of an eye setting inserted

through the neck opening of the doll head and displaced from their normal positions to permit said axis to be cooperatively assembled with the supporting member.

10. In combination with a doll head having front and rear sections adapted to be permanently joined to each other, a member for supporting an oscillatory eye setting upon the front section of the doll head, a retaining member adapted to be cooperatively associated with said supporting member to prevent displacement of the eye setting out of cooperative relation with the latter, means engaged with the retaining member and secured to the head structure for holding the supporting and retaining members in assembled relation with respect to the front wall of the doll head, said supporting member having an inwardly projecting bearing part, and said retaining member including a resiliently yieldable part cooperatively associated with said bearing part and adapted to be engaged by the axis of the eye setting inserted through the neck opening of a doll head and displaced from its normal position to permit said axis to be mounted in operative position upon said bearing part.

11. In combination with a doll head having front and rear sections adapted to be permanently joined to each other, a member for supporting an oscillatory eye setting upon the front wall of the doll head, a retaining member cooperatively associated with said supporting member and having means to prevent displacement of the eye setting out of cooperative relation with the latter, and a single fastening member for said supporting and retaining members having parts expansible under pressure and provided with means for interlocking engagement with the structure of the front wall of the doll head to rigidly fix the several members in applied position with relation to said wall and with respect to each other before the doll head sections are connected.

12. In combination with a doll head having front and rear sections adapted to be permanently joined to each other, a member for supporting an oscillatory eye setting upon the front section of the doll head, a retaining member adapted to be cooperatively associated with said supporting member to prevent displacement of the eye setting out of cooperative relation with the latter, and a single fastening member for said supporting and retaining members engaged with one of said members and having parts expansible under pressure and provided with means for interlocking engagement with the structure of the doll head wall to rigidly fix the several members in applied position with relation to said wall and with respect to each other before the doll head sections are connected, said supporting member having spaced inwardly projecting bearing arms

and said retaining member being provided with spaced resiliently yieldable parts normally engaged with the respective bearing arms and said parts adapted to be displaced from normal position by the engagement of the axis of an eye setting inserted upwardly through the neck opening of the doll head whereby said axis may be operatively positioned upon said bearing arms.

13. In combination with a doll head having front and rear sections adapted to be permanently joined to each other, a member for supporting an oscillatory eye setting upon the front section of the doll head, a retaining member adapted to be cooperatively associated with said supporting member to prevent displacement of the eye setting out of cooperative relation with the latter, and a single fastening member for said supporting and retaining members engaged with one of said members and having parts expansible under pressure and provided with means for interlocking engagement with the structure of the doll head wall to rigidly fix the several members in applied position with relation to said wall and with respect to each other before the doll head sections are connected, said supporting member having spaced inwardly projecting bearing arms and said retaining member being provided with spaced resiliently yieldable parts normally engaged with the respective bearing arms, and said member having an additional resiliently yieldable part positioned between said bearing arms, and said latter part and the first named parts of said retaining member adapted to be successively engaged by the axis of an eye setting inserted through the neck opening of a doll head and relatively displaced from their normal positions to permit said axis to be operatively mounted on the bearing arms, and said last named part of the retaining member adapted to coact with the axis of the eye setting and yieldingly hold the eye members thereon in operative relation to spaced eye openings in the head wall.

14. In combination with a doll head having an internal recess in its front wall, a supporting member for an oscillatory eye setting positioned in said recess, a member superimposed upon the supporting member and having means to retain the setting in assembled relation with the latter, and a plate superimposed upon the retaining member and having means interlocking with the side walls of the recess to permanently fix said supporting and retaining members in relation to each other and with respect to the head wall.

15. In combination with a doll head having an internal recess in its front wall, a supporting member for an oscillatory eye setting positioned in said recess, a member superimposed upon the supporting member

and having means to retain the setting in assembled relation with the latter, and a plate superimposed upon said retaining member within said recess and having parts yieldable under pressure and provided with means adapted to interlock with the structure of the head wall to permanently fix said supporting and retaining members and said plate in position with relation to each other and with respect to the head wall.

16. In combination with a doll head having an internal recess in its front wall, a supporting member for an oscillatory eye setting positioned in said recess and having inwardly projecting bearing means to receive and support the shaft of the eye setting, a second member positioned in said recess and having means adapted to cooperate with the eye setting to urge the same forwardly upon said bearing means and hold the eye members in cooperative relation with spaced eye openings in the head wall, and an expansible element superimposed upon the second member and having means interlocked with the side walls of the recess to permanently fix the said members within said recess against movement with relation to each other and with respect to said head wall.

17. In combination with a doll head having an internal recess in its front wall, a supporting member for an oscillatory eye setting positioned in said recess and having inwardly projecting bearing means to receive and support the shaft of the eye setting, a second member positioned in said recess and having means adapted to cooperate with the eye setting to urge the same forwardly upon said bearing means and hold the eye members in cooperative relation with spaced eye openings in the head wall, and a common fastening member for said first named members extending across said recess and having means at its ends interlocked with the structure of the head wall and permanently securing said members with respect to said wall and against independent movement with relation to each other.

18. In combination with a doll head having an internal recess in its front wall, a supporting member for an oscillatory eye setting positioned in said recess and having inwardly projecting bearing means to receive and support the shaft of the eye setting, a second member positioned in said recess and having means adapted to cooperate with the eye setting to urge the same forwardly upon said bearing means and hold the eye members in cooperative relation with spaced eye openings in the head wall, and a resilient fastening member also positioned in said recess and having parts expansible under pressure into interlocked engagement with the structure of the head wall to thereby permanently secure said members in fixed relation to said wall.

and against independent movement with relation to each other.

19. In combination with a doll head having front and rear sections adapted to be permanently joined to each other, said front section having an internal recess in its wall, supporting and retaining members for an oscillatory eye setting positioned in said recess before connecting the head sections with each other, additional means positioned in said recess and having parts resiliently yieldable under pressure into interlocked engagement with the structure of the head wall to permanently fix said supporting and retaining means in its applied position, and said means including cooperatively related parts, one of which is yieldable relative to the other to permit an eye setting inserted through the neck opening of a doll head after the head sections have been connected to be assembled with said supporting and retaining means in operative relation to spaced eye openings in the head wall.

20. In an eye mounting for dolls, a supporting member having a bearing part upon which the axis of an oscillatory eye setting is adapted to be engaged, a retaining member adapted to be cooperatively assembled with said supporting member and having a part to yieldingly coact with the axis of the eye setting to prevent its displacement out of operative engagement with said bearing part, and a fastening member adapted to be assembled upon said retaining member and having parts expansible under pressure into interlocked engagement with the structure of a doll head wall to permanently fix said members in assembled relation with respect to said wall.

21. In an eye mounting for dolls, a supporting member having a bearing part upon which the axis of an oscillatory eye setting is adapted to be positioned, a retaining member adapted to be assembled upon said supporting member and having an angularly offset resiliently yieldable part to coact with the axis of the eye setting and resist displacement of the same from its operative position upon said bearing part, and a fastening plate having an opening therein through which said angularly offset part of the retaining member is disposed, and said plate having resiliently yieldable parts provided with means adapted for interlocking engagement with the structure of the head wall to secure said plate and said members in permanently fixed assembled relation with each other.

22. In an eye mounting for dolls, a supporting member having spaced angularly projecting bearing parts upon which the axis of an oscillatory eye setting is adapted to be positioned, a retaining member adapted to be assembled upon the supporting member and having spaced resiliently yieldable angularly disposed arms adapted to coact with the re-

spective bearing arms of said supporting member and yieldable with respect thereto to permit the axis of the eye setting to be positioned upon said bearing arms, and said retaining member having an additional resiliently yieldable part to coact with the axis of the eye setting and resist its movement in one direction relative to said arms, and a fastening plate adapted to be assembled upon the retaining member and having parts yieldable under pressure adapted to be imbedded in the structure of a doll head wall to permanently fix said members in assembled relation with respect to said wall.

23. In combination with a doll head having spaced eye openings in its front wall and an internal recess in said wall above the eye openings, bearing means for an oscillatory eye setting having a part at one end fixed to the inner face of said wall and an eye setting supporting part projecting inwardly from said first named part between the eye openings and below said recess, and a retaining member secured to the head wall within said recess having a depending part to coact with a part of the eye setting and retain the same in operative position upon said bearing means.

24. In combination with a doll head having spaced eye openings in its front wall and an internal recess in said wall above the eye openings, bearing means for an oscillatory eye setting projecting inwardly from said wall between the eye openings and below said recess, a member positioned in said recess having a depending part to engage part of the eye setting and retain the same in operative position upon said bearing means, and a fastening element superimposed upon said retaining member within said recess and provided with oppositely projecting prongs impaling the wall structure of the doll head.

25. In combination with a doll head having spaced eye openings in its front wall and a bearing arm projecting inwardly from said wall between the eye openings to receive the axis of an oscillatory eye setting, a retaining member, a fastening plate superimposed upon the retaining member and having oppositely projecting prongs impaling the structure of the front wall of the doll head, and said member including a resiliently yieldable part normally positioned in substantially parallel relation to the front wall of the doll head and having a free end thereof positioned adjacent to the rear end of said bearing arm and displaceable relative thereto to permit the axis of the eye setting to be positioned upon said bearing arm.

26. In combination with a doll head having spaced eye openings in its front wall and vertically spaced internal surfaces on said wall above the eye openings, bearing means projecting inwardly from said head wall between the eye openings and below said sur-

faces, and means for retaining an oscillatory eye setting in operative position upon said bearing means consisting of a member positioned between and engaging the said vertically spaced surfaces having a depending part cooperatively associated with said bearing means and displaceable relative thereto to permit the eye mounting to be operatively positioned upon the bearing means, and means for securing said retaining member against inward movement with respect to said vertically spaced surfaces on the head wall.

In testimony that I claim the foregoing as my invention, I have signed my name hereto.

LEO J. GRUBMAN.
